His Attorney.

UNITED STATES PATENT OFFICE

2,477,985

MULTIPLE TUNING SYSTEM

Donald B. Keim, Bridgeport, Conn., assignor to
General Electric Company, a corporation of
New York

Application January 21, 1948, Serial No. 3,412

5 Claims. (Cl. 74—10.7)

1

This invention relates to tuning systems for radio apparatus and the like, and more particularly to an improved means for tuning simultaneously a plurality of electrical circuits.

It is an object of this invention to provide a tuning system for tuning simultaneously a plurality of electrical circuits, which is compact, simple in construction, and wherein the circuits may be tuned accurately and precisely to any desired setting.

It is a further object of this invention to provide such a multiple circuit tuning system in which the pre-set relationship between the various circuits being tuned is strictly maintained.

Yet, a further object of this invention is to provide a tuning system which may be utilized to tune simultaneously a relatively large number of electrical circuits.

A still further object of this invention is to provide a tuning system that is rugged in construction and non resilient in nature, whereby the calibration of this system is rigidly adhered to.

Yet another object of this invention is to provide a tuning system for tuning simultaneously a plurality of electrical circuits in which the respective tuning elements of the circuits may be simply and conveniently individually adjusted, for alignment purposes.

The features of this invention which are believed to be new are set forth with particularity in the appended claims. The invention itself, however, together with further objects and advantages thereof may best be understood by reference to the accompanying drawing wherein the single figure represents a preferred embodiment of the invention.

Referring now to the figure, shaft 1 represents the tuning control of the proposed mechanism. Shaft 1 may be mounted in any suitable bracket, not shown, this bracket serving as a support for the tuning mechanism. Rigidly mounted on shaft 1 and rotated thereby is a pulley or roller 2, which in turn drives a further pulley or roller 3 which is mounted on shaft 4, the rollers 2 and 3 being coupled together by means of a metallic strap or ribbon in a form of a belt 5 supported by the above-mentioned rollers. The pulleys may more conveniently be mounted in the position shown with the pulley 2 vertically above pulley 3, so that the one side of the belt 5 travels in an upward direction as the other side travels downward. The belt is secured to pulleys 2 and 3 by way of screws 6, the corresponding screws 6 in pulley 2 not being visible in the view shown in the accompanying figure.

2

Crossarms 7 and 8 are attached to belt 5 on opposite sides thereof by means of rivets 9. Any desired number of circuit elements may be adjustably attached to these crossarms. In the present example three such elements are shown, these elements comprising tuning cores 10 and 11, and a tuning vane 12. The tuning cores 10 and 11 and the vane 12 are secured to crossarms 7 and 8 by adjustable clamping screws 13 of the split type, and hexagonal units 13'. It can be seen that for aligning purposes the various cores and vanes may be individually longitudinally adjusted, and clamped by means of screws 13.

Coils 14 and 15 are respectively wound on coil forms 16 and 17, these forms being mounted to a chassis by way of mounts 18 and 19. Similarly, vane 12 forms the movable element of a variable tuning arrangement having a fixed vane 20 mounted in brackets 21, the brackets 21 being mounted to a chassis.

When the tuning shaft 1 is turned by any suitable means, the crossarms 7 and 8 move in diametrically opposite directions and the longitudinal movement of cores 10 and 11 and vane 12 in their corresponding coils and tuning unit may be utilized to effect tuning of the electrical circuits associated therewith.

In the present system, the diameter of pulleys 2 and 3 determine the length of travel of the various cores and vanes with respect to the rotation of tuning shaft 1. It is noted that the diameter of the pulleys 2 and 3 should be large enough to insure full desired longitudinal travel of the tuning elements with less than 180° rotation of the pulleys.

This invention, therefore, provides an improved tuning arrangement in which a plurality of electrical circuits may be tuned simultaneously, and wherein the crossarms 7 and 8 may be extended to include any practical number of tuning elements for such circuits.

This invention has a further advantage in that the utilization of a metal strap precludes stretching thereof and the mechanism is capable of holding its calibration to a high degree of accuracy. Furthermore, the provision of the adjustable clamping screws 13 makes possible the facile adjustment of the individual elements of the electrical circuit for aligning purposes.

While a certain specific embodiment has been shown and described, it will of course be understood that various modifications may be made without departing from the invention. The appended claims are therefore intended to cover

any such modifications within the true spirit and scope of the invention.

What I claim as new and desire to secure by Letters Patent of the United States is:

1. A tuning mechanism for imparting longitudinal motion simultaneously to a plurality of tuning elements, comprising, a driving shaft member having a roller member mounted thereon, an idler shaft member having a further roller member mounted thereon, a flexible continuous strap coupling said first-mentioned roller member to said further roller member, crossarm means mounted on said flexible strap, and means for coupling said tuning elements to said crossarm means.

2. A tuning mechanism for imparting longitudinal motion simultaneously to a plurality of tuning elements, comprising, a driving shaft member having a roller member mounted thereon, an idler shaft member having a further roller member mounted thereon, a flexible continuous strap coupling said first-mentioned roller member to said further roller member, a pair of crossarms mounted on opposite sides of said flexible strap, means for coupling said tuning elements to said crossarms, and means for fixing said flexible strap to said roller members.

3. A tuning mechanism for imparting longitudinal motion simultaneously to a plurality of tuning elements, comprising, a driving shaft member having a roller member mounted thereon, an idler shaft member having a further roller member mounted thereon, a flexible continuous strap coupling said first-mentioned roller member to said further roller member, a pair of crossarms mounted on said flexible strap, means for coupling said tuning elements to said crossarms, and means for individually adjusting the longitudinal position of said tuning elements.

4. A tuning mechanism for imparting longitudinal motion simultaneously to a plurality of tuning elements, comprising, a driving shaft member having a roller member mounted thereon, an idler shaft member having a further roller member mounted thereon, a flexible continuous strap coupling said first-mentioned roller member to said further roller member, a pair of crossarms mounted on said flexible strap, and individually adjustable coupling means for coupling said tuning elements to said crossarms.

5. In a radio tuning system, a plurality of tuning circuits wherein longitudinal motion of tuning elements associated with said respective circuits effects the tuning thereof, means for imparting longitudinal motion to said tuning elements, said means comprising a pair of roller members spaced apart one from the other, a driving shaft and an idler shaft supporting said respective roller members, a continuous flexible strap coupling said roller members, crossarm means mounted on said flexible strap, and means for coupling said tuning elements to said crossarm means for longitudinal motion of said elements in response to rotation of said driving shaft.

DONALD B. KEIM.
